EXPANDER TOOL

Albert J. Scholtes, Baltimore, Md., assignor to
Scovill Manufacturing Company, Waterbury,
Conn., a corporation of Connecticut

Application November 1, 1938, Serial No. 238,275

5 Claims. (Cl. 153—82)

The present invention relates to a tool for expanding grooves in tubes, hose coupling nipples and the like.

The purpose of this invention is to provide means for retaining the expander ball or balls in the one or more radial openings in the mandrel of the tool. This admits of the carrying, conveniently, of the expander tool in a tool box for easy access without the necessity of exercising undue care, and without the liability of loss of the balls, in handling and transporting the tool.

Another object of the invention is to provide a relatively small, light weight and compact tool so constructed as to possess the required strength, and which has the tube deforming elements so disposed as to offset unequal expansion or distortion of the tube itself during the grooving of the tube.

A further object of this invention is to improve 20 and make practical the type of expander exemplified in the patent to Hoyer No. 568,574 granted September 29, 1896.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevation of an expander tool embodying the features of this invention, the tool being ready for insertion in a hose coupling shown.

Figure 2 is a similar view but with the tool disposed in the coupling prior to the expanding operation, the coupling being shown in section.

Figure 3 is a transverse section taken through the same on the line 3—3 of Figure 2.

Figure 4 is a view similar to Figure 3 but where- 40 in the expanding operation has been carried out to at least a partial extent.

Figure 5 is a transverse section taken through the same on the line 5—5 of Figure 4.

Figure 6 is a perspective view of the expander 45 tool with the parts partly separated from one another.

Figure 7 is a longitudinal section taken through the expander tool, the expander balls being re- tracted.

Figure 8 is an enlarged transverse section taken through the same on the line 8—8 of Figure 7.

Figure 9 is a longitudinal section taken through the tool, the expander balls being extended.

Figure 10 is an enlarged transverse section

taken through the same on the line 10—10 of Figure 9.

Figure 11 is an enlarged fragmentary sectional view in perspective of the side wall of the mandrel of the tool, showing the retaining spring in its 5 groove and the latter intersecting the ball opening, and

Figure 12 is a detail sectional enlarged view of the wall of the mandrel, showing a slight modification of the spring groove in the wall. 10

Referring now to the drawings, and first to Figures 6 to 11, the tool has a hollow mandrel or shaft 25 adapted for insertion in the tube or nipple to be expanded or beaded. The mandrel 25 is open at opposite ends and at one end has an 15 enlarged head or nut 26 serving to turn the mandrel in the tube and to determine the distance of insertion of the mandrel in the tube.

The mandrel 25 has two pairs of axially spaced apart openings 27 and 28 through its side walls, 20 the openings of each pair being diametrically opposed and the axis of the openings 27 being at right angles to the axis of the openings 28. The openings 27 and 28 are thus disposed in staggered relation substantially ninety degrees apart around 25 the mandrel. Each opening 27 and 28 provides a socket for a ball 29 adapted to slide radially through the wall of the mandrel 25.

The mandrel 25 has a core pin 30 fitting for axial sliding and turning movements in the mandrel. One end of the core pin 30 has an enlarged nut head 31 and has a threaded portion 32 adjacent the head 31 and which has threaded engagement in the mandrel head 26 so as to move the core pin 30 lengthwise in the mandrel 25 35 when turned therein. The nut head 31 also has the function of limiting the advancement of the core pin 30 through the mandrel by abutting the nut 26 of the latter. Withdrawal of the core pin 30 through the mandrel 25 is limited by a stop 40 washer 33 removably secured against the free end of the core pin 30 by a headed screw 34 or the like.

The core pin 30 is provided with an axial cam 35 for each pair of balls 29. The cams are in the form of cones axially spaced apart a distance equal to the space between the pairs of openings 27 and 28 and have an intermediate shoulder 36 between them. The apices of the cams 35 merge into stems 37 which flare into the adjacent shoulder 36 and the end portion of the core pin and provide annular recesses in the core pin 30 with rounded bottom walls forming bottoms for the socket openings 27 and 28 of the mandrel. When in normal position ready for use, as shown in Fig- 55

ure 7, the stems 37 are in transverse registration with their respective openings 27 and 28 so that the balls 29 are fully retracted and lie within the peripheral surface of the mandrel 25.

5 The stems 37, forming the bottoms of the ball sockets, are proportioned in diameter to hold the balls 29, when retracted, substantially flush with the outer surface of the mandrel and with the balls 29 remaining sufficiently in the openings 27 10 and 28 to guide the balls outwardly when acted upon by the cams 35. A comparison of Figures 7 and 9 shows that by screwing the core pin 30 into the mandrel 25 the cams 35 are advanced beneath the balls 29 and force the latter outwardly 15 in the openings 27 and 28. The force exerted upon the balls 29 depends upon the pitch of the threads 32 and the length or angle of the cones 35. Means is provided for yieldingly retaining the balls 29 in their sockets when retracted so that 20 the balls cannot be lost or fall out of the tool, even when dropped and roughly handled. This means comprises an annular groove 38 in the inner wall of the mandrel 25 for each pair of openings 27 and 28.

25 As shown clearly in Figures 7, 8, 11 and 12, the groove 38 has a bottom wall which is inclined transversely of the groove so that one side of the groove is deeper than the other side. The deeper side of the groove 38 has an abrupt shoulder side wall 39 and intersects one side of the adjacent opening 27, or 28. In each groove 38 is sprung a split spring ring 40 bearing against the inclined bottom wall of the groove and deflected thereby against the shoulder wall 39 and across 30 the sides of the opening 27, or 28. Preferably, the annular grooves 38 are disposed across the sides of the openings 27 and 28 nearer the nut or head 26 of the mandrel, or at the sides of the openings 27 and 28 which are out of the line of 35 thrust of the balls 29 when projected by the cams 35.

Normally, portions of the spring rings 40 are exposed in the sides of the socket openings 27 and 28 and bear against the adjacent portions of the 40 balls 29. When the balls 29 are retracted, as shown in Figure 7, the springs 40 engage the balls 29 outwardly of their largest diameter portions and retain the balls 29 in their seats and from accidental dislodgement from the mandrel. 45 The depth of the ball sockets and the position of the springs 40 relative to the diameter of the balls 29 is such that the balls may be projected to an appreciable extent before the largest diameter portion of the balls pass the springs 40 and the latter cease to perform their ball retaining function. When the expander tool is in position in the tube or other work, the tube holds the balls 29 from springing out of the sockets, and the tube serves to force the balls 29 back 50 in their sockets when the cams are shifted and the tool withdrawn from the tube.

As shown in Figure 12, the shallow side of the groove 38 may have a narrow shoulder wall 41 extending from the adjacent side of the inclined bottom wall 39 opposite to the stop shoulder wall 39. This assists in maintaining the spring ring 40 in the groove during assembling and handling of the tool.

While this expander tool is adapted to various 70 types of tubes and nipples for expanding one or more annular beads therein, Figures 1 to 4 illustrate the tool as applied to one form of the hose coupling for securing the end of a hose 42 in the coupling member.

75 As shown in Figure 1, the expander tool is ad-

justed with the balls 29 retracted and ready for insertion in the hose coupling. The coupling illustrated comprises a nut 43 shouldered at one end and having a nipple 44. The tool is inserted in the coupling as shown in Figure 2. The nut head 26 of the mandrel limits the insertion of the mandrel and determines the locations of the beads to be expanded.

The nut head 26 is held stationary and the core pin 30 is turned up in the mandrel as 10 shown in Figure 4. The core pin 30 is advanced a short distance when the entire tool is rotated in the nipple 44. This may be accomplished by a wrench or the like applied to the nut head 26. Then the core pin is further advanced and the 15 tool again rotated. This alternate advancement of the core pin and the turning of the tool is carried on until annular beads 45 of the desired height are expanded in the wall of the nipple 44. These beads 45 press into the inner wall of the 20 hose 42 and securely anchor and seal the coupling.

After the beads 45 have been formed the core pin 30 is turned backward to release the balls 29, and the sides of the beads 45 retract in their sockets as the mandrel 25 is withdrawn from the coupling so that the springs 40 may then act to retain the balls from failing out of the mandrel.

What is claimed is:

1. In a tube expander, a mandrel having a socket opening in its side and adapted for insertion in a tube, a ball seated in the opening, means for advancing the ball outwardly in the opening for expanding the tube, and a circumferential 35 spring seated in the interior surface wall of the mandrel across one side of the opening thereof and engaging the side of the ball to yieldingly retain the ball in the socket opening when the ball is retracted.

2. In a tube expander, a mandrel having a socket opening in its side and adapted for insertion in a tube, a ball seated in the opening, means for advancing the ball outwardly in the opening for expanding the tube, said mandrel having an 45 annular groove in its inner wall intersecting one side of the socket opening and having a cam portion inclined toward said opening, and a spring sprung into said groove against said cam portion and urged thereby against one side of 50 the ball to retain the same in the socket opening when the ball is retracted.

3. An expander for tubes and hose couplings, comprising a mandrel for insertion into the tube, a core pin movable in the mandrel, means for 55 axially shifting the pin in the mandrel, said mandrel having an opening through the side wall thereof and said core pin having a cam portion adapted to register with said opening in the mandrel, a ball seated on said cam portion and 60 lying in said opening and adapted to be projected therethrough upon the shifting of said core pin in the mandrel, said mandrel having an annular groove in its inner wall intersecting one side of the opening, and a spring sprung into said groove 65 in the inner wall of the mandrel and extending across the side of the opening for yieldingly engaging the ball and retaining the same in the opening.

4. An expander for tubes and hose couplings, 70 comprising a mandrel for insertion into the tube, a core pin movable in the mandrel, means for axially shifting the pin in the mandrel, said mandrel having an opening through the side wall thereof and said core pin having a cam portion 75

adapted to register with said opening in the mandrel, a ball seated on said cam portion and lying in said opening and adapted to be projected therethrough upon the shifting of said core pin in the mandrel, said mandrel having an annular groove in its inner wall intersecting at one side said opening at the side thereof and having its bottom face inclined backwardly from the opening and having a shoulder at said opening intersecting side, and a spring ring sprung into said groove and normally urged by said inclined face toward the shoulder and against the ball in the opening.

5. An expander for tubes and hose couplings, comprising a mandrel for insertion into the tube, a core pin movable in the mandrel, means for axially shifting the pin in the mandrel, said

mandrel having an opening through the side wall thereof and said core pin having a cam portion adapted to register with said opening in the mandrel, a ball seated on said cam portion and lying in said opening and adapted to be projected therethrough upon the shifting of said core pin in the mandrel, said mandrel having below its outer surface a groove with an inclined bottom wall and a shoulder side wall at the deeper side of the groove, said groove intersecting at its deeper side one side of the opening, and a retaining element sprung into the groove against said inclined bottom wall and deflected thereby toward said shouldered wall and against the ball in the mandrel opening to 15 retain the ball therein.

ALBERT J. SCHOLTES.
